UNITED STATES PATENT OFFICE.

RUSSELL A. TROMBLEY, OF AKRON, OHIO.

COLLAPSIBLE KITE.

Application filed May 26, 1921. Serial No. 472,690.

To all whom it may concern:

Be it known that I, RUSSELL A. TROMBLEY, a citizen of the United States, residing at Akron, in the county of Summit and State 5 of Ohio, have invented certain new and useful Improvements in Collapsible Kites; and I do declare the following to be a full, clear, and exact description of the invention, such as will enable others skilled in 10 the art to which it appertains to make and use the same.

This invention relates to improvements in kites, and has for its principal object to provide a device of this class which is of such 15 construction that it can be collapsed and rendered extremely compact for shipping and storing purposes.

Another and important object of the invention is to provide a collapsible kite embodying a knock-down frame which includes the usual vertical stick and a sectional cross-stick, together with a suitable paper or other kind of covering for the frame which is held on the latter by means of a marginal cord, 25 there being novel means employed for simultaneously bowing the cross-stick and stretching the covering tightly over the frame.

A further object of the invention is to 30 provide a kite wherein the sections of the cross-stick are permanently connected to the cords for bowing said stick and stretching said covering, thus holding said sections in the proper position for quick and easy assemblage of the kite and preventing accidental displacement or loss of any of the parts 35 of the latter.

A still further object of the invention is to 40 generally improve upon devices of this class by the provision of one of extreme simplicity and durability, the parts employed being few and simple in construction and the entire device being rendered extremely inexpensive to both the manufacturer and 45 the user.

Still another object of the invention is to 50 provide a kite having a bridle or attaching band for the holding cord or line, this bridle including a shaft on which a spinning device 55 is rotatably mounted, the device being located between the lower end of said bridle and point of attachment of the holding cord so that the shaft will be disposed substantially horizontal when the kite is in the flying position, thus insuring a continued rotation of 60 the spinning element at all times.

Other objects and advantages of the invention will become apparent during the course of the following description.

In the accompanying drawings forming a 60 part of this specification and in which like numerals are employed to designate like parts throughout the same;

Figure 1 is a front elevational view of a kite constructed in accordance with this invention. 65

Figure 2 is a horizontal sectional view taken substantially on the plane of the line 2-2 of Fig. 1.

Figure 3 is a side elevational view of 70 Fig. 1.

Figure 4 is a top plan view of the kite collapsed and partially folded.

Figure 5 is an enlarged detail perspective view of one of the upper corners of the kite. 75

Figure 6 is a detail perspective view showing the manner in which the sticks are connected with one another.

Figure 7 is an enlarged detail sectional view of the spinning device. 80

Referring to the drawings by numerals, 1 designates a vertically disposed stick of suitable form such as is generally employed in the make-up of kites. This stick constitutes a part of the frame. The frame is completed 85 by the employment of a cross-stick made up of sections 2 which have their inner ends received in the sockets in the opposite ends of a connector 3 carried by the stick 1. With this construction, it will be seen that 90 the frame can be assembled and disassembled to render it extremely compact for shipping and storing purposes. As is customary, a tissue paper covering of suitable

design, designated by the numeral 4, is 95 stretched across this frame and attached thereto by means of a cord 5 which may be conveniently termed the marginal cord since it is fastened in any suitable way to the margin or edge of the paper 4, being attached by short pieces of cord to the opposite ends of the stick 1 as indicated at the points 6. The upper corners of the paper covering are cut away to expose the marginal cord as indicated at the points 7 and 100 two short additional cords 8 and 9 are connected to these exposed portions of the marginal cord as indicated at the points 7 and holes at the outer ends of the sections 2 of the cross-stick. The cord 9 is formed at its free end with a loop 10 and the remaining cord 8 is equipped with a hook 11 which is 110

connected with this loop in order to connect the two cords together. It is to be noted that the combined lengths of the cords 8 and 9 is less than the combined length of the sections 2 which compose the cross-stick referred to. Therefore, when the hook 11 is engaged with the loop 10, this causes the cross-stick to bow, and since these cords 8 and 9 are connected with the marginal cord 5, such connecting of the ends together simultaneously stretches the tissue paper covering 4 over the frame to complete the kite. Hence, it will be seen that these cords 8 and 9 serve a double function which, as far as I know, is not accomplished by any prior patented or marketed kites. I also wish to direct attention at this point to the fact that the sections 2 of the cross-stick are not provided with notches at their extremities as is usual but are formed with holes for passage of the cords 8 and 9. Because of this, they are practically permanently connected with these cords and there is little or no chance of them becoming accidentally displaced or lost as may otherwise occur. This is also extremely advantageous, as before pointed out, in that it holds the sticks in a convenient position for permitting ready assemblage of the kite frame. This leads me to say that the kite frame by the way is much simpler and stronger than frames heretofore employed, attention being especially directed to the simple and novel coupling 3 employed. The kite in addition to embodying the parts so far described, is equipped with additional strings or cords 12 and 13 which are connected at their outer ends with the vertical stick 1 and when connected together constitute what may be termed the attaching bridle to which the holding cord or line 14 is connected. If desired, a small ring 15 may be carried by the cord 12 for convenient connection of this holding cord 14. It is to be noted at this point that the inner ends of the cords 12 and 13 are connected to eyes 16 at the opposite ends of a shaft 17 which has a bladed spinning element 18 rotatably mounted thereon. I may state that this element 18 may be of any suitable construction, being preferably constructed as disclosed. While it might not be necessary, I prefer to employ bearings 19 which are interposed between the eyes 16 and metal center of the rotary element 18, these being employed to insure easy and fast rotation of said element. I wish to lay emphasis on the fact that the rotary element and parts which contact therewith are arranged at a point on the bridle below the point of connection of the holding cord 14 and when the kite is in the air, the shaft 17 assumes an approximately horizontal position, thus disposing the blades of the rotary element in such relation to the wind as to insure a continued rotation

of this element at all times and under all conditions. Practical use of the device has proven that the above result is obtained.

It is yet to be mentioned that a tail, designated generally by the numeral 20, is detachably connected by a socket connection 21 with the lower end of the main vertical stick 1. This tail may be shaped in any way, being preferably substantially oval-shaped, thus enabling it to function somewhat like a rudder to guide and properly balance the lower end of this kite to prevent the same from turning over and diving toward the ground as often occurs. While it might not be necessary, I desire to point out that the design of an airplane or other attractive design such as shown will be preferably printed or otherwise placed on the tissue paper covering 4, to increase the attractiveness of the kite. This attractive cover together with the novel spinning device will provide much amusement for small children and the structure of the kite will be found advantageous from the shipper's standpoint.

It is obvious that in order to collapse the kite, it is only necessary to grasp the inner ends of the sections 2 and disconnect them from the socket connector 3 and arrange them alongside the main stick 1 as indicated in Fig. 4, then the kite can be rolled or folded into a compact package for shipping and storing. As before pointed out, the cross-sticks 2 are practically permanently connected with the bowing cords 8 and 9 and they will thus be held in convenient position for easy and ready assembling of the kite after it is unfolded. Hence, a small child will be able to assemble this kite.

While it is not essential, the lower end of the cord 13 which constitutes a part of the bridle as referred to is connected with the vertical stick after passing through an apertured reinforcing paper disk 22 glued or otherwise secured to the front face of the tissue paper covering.

The several features of the invention and construction and arrangement of the various parts together with the manner of using and assembling the same will no doubt be understood by considering the foregoing description in connection with the drawings. In view of this, a more lengthy and detailed description is deemed unnecessary.

In all probability, the best possible results can be obtained with the specific construction and arrangement herein shown and described. Nevertheless, I wish it to be understood that minor changes in shape and size coming within the scope of the subjoined claims may be resorted to if desired.

I claim:

1. A collapsible kite comprising a vertical stick, a horizontal sectional cross-piece,

the sections of which have detachable connection with said stick and are provided at their outer ends with holes, a marginal cord connected with the opposite ends of 5 said stick, and other cords for bowing the cross-piece, being connected at their outer ends with said first named cord, being then passed through the aforesaid holes and detachably connected together at their inner 10 ends.

2. A collapsible kite comprising a vertical stick having a transverse connector near its upper end, said connector being provided in its opposite ends with sockets, a cross-

piece composed of two comparatively short 15 sticks having their inner ends removably received in said sockets and being provided at their outer ends with holes, a covering for the sticks, a marginal cord connected to said covering and said vertical stick, and 20 relatively short pieces of cord passing through the aforesaid holes, being connected at their outer ends to said first named cord and being detachably connected together at their inner ends. 25

In testimony whereof I have hereunto set my hand.

RUSSELL A. TROMBLEY.
